UNITED STATES PATENT OFFICE.

ELMER E. SCHELLENGER, OF RIVERSIDE, CALIFORNIA.

DISTRIBUTER FOR DUMPING WAGONS AND CARS.

1,029,894.

Specification of Letters Patent. Patented June 18, 1912.

Application filed November 14, 1910. Serial No. 592,399.

To all whom it may concern:

Be it known that I, ELMER E. SCHELLENGER, citizen of the United States, residing at Riverside, in the county of Riverside and State of California, have invented certain new and useful Improvements in Distributers for Dumping Wagons and Cars, of which the following is a specification.

In building highways and railroad road-beds, sand, gravel, crushed stone, broken rock or ballast are usually carried to the place selected for dumping the wagons or cars and the load then dumped at successive points, the load after it is dumped being distributed to a proper and uniform depth along the road by manual labor or by means of scrapers afterward driven along the line of the road. The load may be distributed to some degree by driving the dumping wagon at a certain rate of speed over the surface to be filled and allowing the load to be continuously discharged from the wagon as it moves. While this secures a certain distribution for the load, it does not secure a uniform distribution thereof and does not provide any means for leveling the surface of the broken stone, sand, gravel, etc., so as to secure a uniform depth of the road-making material.

The primary object of my invention is to provide means for gradually discharging under control the contents of a dumping wagon or car, and particularly to provide a means used in connection with dumping wagons or dumping vehicles of any character whereby the load carried by such vehicle may be continuously discharged therefrom and distributed to a uniform depth along the bed of a highway, railroad or like situation and to provide in connection therewith means whereby the surface of the load so distributed may be evened off and given any desired lateral inclination or crown as the dumping wagon moves forward, and without the necessity of employing manual labor for this purpose.

Another object is to provide a very simple and easily operated road distributer which shall be capable of ready attachment between the discharge opening of a dumping wagon and which then, as the dumping wagon moves forward along the line of the roadbed, will act to distribute the load being discharged from said wagon to a uniform depth, and will act to level the sur-

face of the material so discharged, and which after the load has been fully discharged may be easily detached from the dumping wagon in position ready for attachment to the next filling wagon, thus providing means whereby each wagon may move forward along the line of the roadbed discharging and distributing its load.

My invention contemplates the use of a dumping wagon having a transversely extending discharge opening, and the provision beneath said discharge opening of a detachable distributer which is supported upon runners or wheels moving over the roadbed itself and which properly distributes the load discharged from the wagon, and which levels said load and prevents the too rapid discharge of the contents of the wagon, this distributer having the general form of a hopper supported upon runners or wheels and detachably engaged with the dumping vehicle, and provided with an adjustable scraper or leveler.

My invention is shown in the accompanying drawings wherein:

Figure 1 is a side elevation of a dumping wagon showing my attachment applied thereto. Fig. 2 is a rear view thereof showing one manner of distributing the load, the deposited material being shown in section. Fig. 3 is a plan view of the distributing attachment connected to the shackle on the wagon axle.

Corresponding and like parts are referred to in the following description and indicated in all the views of the accompanying drawings by the same reference characters.

Referring to these figures 2 designates a wagon box of a dumping vehicle of any desired character which as shown is mounted upon wheels. I do not wish to be limited to any particular form of this vehicle save that it should be provided with a discharge opening extending transversely across the bottom of the vehicle. As shown in the drawings, the vehicle is provided with a hopper 3 located beneath the wagon body, this hopper at its lower end being provided with a transverse discharge opening. This opening is closed by a door or gate 4 of any desired character. Preferably, however, the door 4 as illustrated is pivoted at its forward end on oppositely disposed links 5 connected to eyes 6, an eye and a link, 5 and 6, being placed upon each side of the hopper 110

3. The lower end of each of the links 5 is provided with an eye to which is attached a flexible connection or cord 7 which passes over suitable rollers or pulleys around an actuating device and is connected at its other extremity with an eye 8 formed upon the end of a link 9. This link 9 extends beneath the middle of the door 4 and is pivotally connected therewith in any suitable manner.

4. In detail, each of the cords 7 passes from the extremity of the link 5 over a pulley 10 attached to the side of the wagon box, and from thence passes over a capstan 11 mounted upon the forward end of the wagon. From the capstan the cord 7 passes rearward and over a pulley 12 and from thence down to the eye of the link 9 as previously described. The capstan may be of any suitable character but as shown is provided with a ratchet wheel and pawl 13 and with a toothed wheel 14 with which a spring-actuated bolt 15 mounted upon a handle 16 engages. The bolt 15 is connected to a hand-grip 17 whereby it may be lifted to permit the lever 16 to be shifted.

5. It will be obvious that by reciprocating the lever 16 that the toothed wheel 14 may be rotated in either direction. It will also be seen that the cord 7 is attached at both ends to the door and that as a consequence a rotation of the capstan 11 will cause the door 4 to slide forward from beneath the bottom of the hopper and in the position shown in dotted lines in Fig. 1, thus disclosing the mouth of the hopper and allowing the contents of the wagon to be discharged.

6. My distributor and leveling attachment comprises a hopper 18, the sides of which are straight. The front of the hopper is formed by a plate 19 which extends downward below the open bottom of the hopper, as shown in Fig. 1, while the rear end of the hopper is formed by a plate 20 which extends downward and inward at an inclination and then vertically downward to the lower edges of the sides of the hopper.

7. Attached to the front plate 19 are the downwardly extending parallel bars 21 which at their lower ends are bent as at 22 and extended forward and attached each to a flat runner 23. A brace 24 extends downward and forward from the upper end of each of the bars 21 and is attached at its lower end to the runner 23 at about its middle.

8. Attached to the sides of the hopper 18 are the draft bars 25 which extend forward to any desired point and are connected at their forward ends by a transverse bar 26 which is provided at opposite points of its length with the bends or loops 27.

9. Attached to the forward end of the wagon in any desired manner and preferably to the front end of a shackle bar 28. This com-

prises a transverse portion which at its ends is bent to form hooks adapted to engage with the loops or bends 27. After forming the hooks the bar 28 at its ends is bent so as to extend at right angles to the transverse portion of the shackle and is then formed with eyes 29 whereby it is pivotally attached to the wagon axle. It will be seen that this shackle constitutes a double hook which may be easily connected to the cross bar 26 or as easily disconnected therefrom. The shackle 28 is raised or lowered by any suitable connection on the wagon and preferably as shown by connecting the shackle to a link or links 30 which in turn are connected to a bifurcated elevating rod 31 which is held in a raised or lowered position in any suitable manner.

10. It will be particularly noted from Fig. 1 that the rear lower edge of the hopper 18 is considerably higher than the forward lower edge of the hopper which extends downward nearly to the runners 23. Attached to the vertically extending portion of the rear end of the hopper 18 is the adjustable leveling plate 32. This plate as will be seen in Fig. 2 has a plurality of vertical slots through which pass stud bolts extending outward from the vertical portion of the rear end 20 of the hopper. It will be obvious that the leveling plate 32 may be thereby adjusted vertically and that it may be adjusted so as to have a slight angularity with relation to the face of the roadbed, if desired.

11. In order to provide for clearing stones or very small obstructions from or in front of the runners 23 so that the hopper may be kept at a proper elevation, I provide each of the runners with an angular scraper 34 which is mounted upon the outside edge of each runner in any suitable manner as by the angle irons 35 and which extends to the forward end of the runner and is then bent inward and forward as at 37, the front forward end of the scraper 36 being practically in line with the inner edge of the runner. I thus eliminate any chance of the runners being lifted upon passing over small stones or other obstructions and thus prevent the hopper from getting out of a parallel relation to the level of the road upon which the load is being dumped.

12. Hinged mounted upon the sides of the hopper are the side boards 38, these side boards being so constructed as to turn up into a vertical position extending above the upper edge of the hopper 18. This is necessary where the wheels of the wagon, car or other vehicle are traveling upon a surface raised above the level of the surface upon which the runners 23 are traveling, as under these circumstances the mouth of the discharging hopper 3 would be at such a height above the distributing hopper 18 that the

material would not be discharged into the hopper 18 but some of it would escape around the sides of the hopper 18.

The operation of this invention in the making of roads is as follows. The distributor 18, mounted upon runners or wheels as may be desired, is placed at any desired point, as for instance the point of commencement of the work. A wagon load of material is then brought to this point and the wagon so guided that the horse on the off-side of the team passes to the right, and the horse on the near side of the team passes to the left of the distributor. The wagon is drawn ahead until the shackle 28 is in proper relation to the bar 26. The vehicle may be then stopped and the shackle engaged with the bends 27 on the bar 26. It is possible, however, to lower the shackle 20 and engage the bar 26 without stopping the vehicle. After this engagement has been made, the gate to the hopper 3 is opened by reciprocating the lever 16, as before described. The team moves forward at a slow 25 rate of speed, drawing with it the wagon and the distributor 18. The load, meanwhile, is discharged through the mouth of the hopper 3 and into the hopper of the distributor and is distributed onto the roadbed 30 to a uniform depth and with a uniform width, as shown by the cross section in Fig. 2. As soon as the load has been fully discharged and the level of the broken stones, gravel, etc., has fallen slightly below the 35 mouth of the hopper 3, and before the broken stones, gravel etc. have sunk below the upper edge of the distributing hopper 18, the driver stops the team and disengages the shackles 28 from the draft bars 25. He 40 then drives ahead and then, by means of the lever 16, reversely operates the flexible connection 7 to close the gate 4. This process is repeated by successive wagons until the material has been distributed for any desired 45 distance in a continuous and unbroken mass of uniform width and of uniform depth. If it is desired to increase the strip of roadbed thus distributed, it may be done in either of two ways. A parallel strip of 50 road-making material may be distributed upon the road close against the top edge of either or both sides of the strip of material already distributed. Second, by repeating the first process and distributing a parallel 55 strip or strips of material with an interval between the strips, this interval to have about the same width but being a little narrower than each parallel strip previously distributed. These intervals between the first 60 named strips of roadbed may be afterward filled to a uniform depth by driving the wagon upon the parallel strips of road-making material first distributed and by turning up the side boards 38, as previously 65 described. Fig. 2 shows a cross section of a

roadbed with two parallel strips of road-making material so placed as to leave an interval between the strips, which interval may be afterward filled as above described.

It will be obvious that my device permits 70 dumping vehicles containing road-making material to be discharged over any area of any desired width or length, and provides for a continuous and uniform distribution of material having a uniform depth and a level 75 surface. It will also be seen that my attachment permits broken stone, gravel, ballast or other road-making material to be distributed over any area of any length, each way from a center so as to present a stepped 80 concave or convex cross section across the entire width of the area being covered, and that after rolling, as in the case of a roadway construction, this stepped convex cross section will give a convex roadway in cross 85 section.

While I have shown the distributing hopper 18 as being mounted upon runners 23, I do not wish to be limited to the use of runners for this purpose as it is obvious that 90 wheels or any other supporting means which is able to travel over the ground might be used. Neither do I wish to limit myself to any particular form of dumping wagon and gate therefor as it is obvious that other 95 forms of dumping vehicle than that shown, provided with other forms of discharge gate might be used without departing from the spirit of the invention.

It will be seen that the depth of the material to be distributed depends entirely upon the adjustment of the leveling plate 32. If this plate is forced downward to its full extent, the depth of the material discharged 100 will be relatively slight. If, however, the plate is drawn up to its full height, it will 105 be relatively deep. As the machine advances along the road this scraper plate, together with the rear end of the hopper, will force the crowded material forward so as 110 to distribute the material to any depth desired. It will be seen that the sides of the distributing hopper 18 will prevent the material from being crowded laterally by the forward passage of the leveling plate or 115 scraper 32 and the rear end of the hopper, which would be the case if only the leveling plate were used. It is also to be noted that by reason of the fact that the front of the hopper extends down below the sides and 120 rear thereof, that the material discharged from the distributing hopper is prevented from being discharged in front of the hopper but is guided rearward, thus causing the material to pack in a much better manner 125 than if the plate or front 19 of the hopper only extended as far down as the bottom edge of the mouth of the hopper 18. Furthermore, it is to be noted that the sides of the hopper 18 are not extended downward 130

for the reason that this would prevent the proper lateral discharge of the material, and for the same reason the runners, wheels or other supporting members upon which the 5 distributing hopper is mounted, and by which it is supported at a predetermined distance above the surface of the road upon which the material is being placed, are located forward of the body of the hopper 18 10 so as not to present any obstruction to the lateral and rearward discharge of the material from the distributing hopper 18. The distributor, as above described, is so connected to the wagon that it will rise and fall independently of any vertical movement of the 15 wagon body itself. Thus while the wheels of the wagon or other vehicle are traveling upon one elevation, the runners, wheels or other supporting members of the distributing hopper may travel upon a lower or 20 different elevation, and it will also be seen in this connection that any irregularity of motion communicated to the wagon itself by passing over the surface for instance of the broken stone will not be transmitted to the distributor which travels upon the surface 25 of the roadbed itself, which surface has been cleared in front of the runners, wheels or other supporting members by means of the clearers or scrapers 37.

While I have illustrated my distributor as used with a wagon having a discharge opening disposed about midway of the wagon body, it will be obvious that the distributor 35 might be used with a wagon discharging in any other manner, as for instance from the rear, it only being necessary that the distributor shall be disposed immediately beneath the discharge opening of the wagon 40 so that the load as it is discharged from the wagon body will pass into the discharging hopper and by said hopper be distributed properly and to an even depth along the roadbed.

45 What I claim is:

1. A distributing attachment for dumping wagons including a hopper into which the dumping wagon is adapted to be discharged, supporting members on which the 50 hopper is mounted, means for connecting the hopper and supporting members to said wagon, said means permitting the hopper and supporting means to rise and fall independently of the wagon, and hinged side 55 boards attached to the sides of the hopper and movable into a vertical position in line with but above the hopper.

60 2. A distributing attachment for dumping vehicles including a hopper open at the top and bottom and comprising opposed sides, a rearwardly and downwardly inclined front and a rear end, the front end of said hopper extending downward and rear-

ward below the sides and rear end of the hopper, runners disposed beneath the forward end of the hopper, angular supports extending down against the front side of the front end of the hopper and extending along and attached to said runners, and draft bars attached to the sides of the hopper and to said runners and extending forward and adapted to be connected to a wagon to permit free vertical movement of the distributing attachment independent of the wagon.

75 3. A distributing attachment for dumping vehicles, including a hopper open at top and bottom, supporting members attached to the forward ends of the hopper extending below the bottom of the same and adapted to support the hopper with its mouth above the ground, means whereby said supporting members and hopper may be pivotally connected to a vehicle for free vertical movement, and clearing scrapers carried by and 80 disposed in front of said supporting members.

4. The combination with a dumping wagon having a discharge opening extending transversely across it and opposed members extending longitudinally of the wagon and having rearwardly extending hooked terminal ends formed each with an open hook 90 opening toward the front of the wagon, of a distributor disposed beneath the discharge end of the wagon and including a supporting frame, a transversely extending distributing member, upwardly and forwardly extending members on the frame, and a transverse bar attached to the forward ends of said members and adapted to be loosely and detachably engaged by the 95 hooks beneath the wagon.

5. The combination with a dumping wagon having a discharge opening extending transversely across it, opposed members 105 extending longitudinally of the wagon and having rearwardly extending hooked terminal ends formed each with an open hook opening toward the front of the wagon, and means disposed upon the wagon whereby the said hooked members may be raised and lowered, of a distributor disposed beneath the discharge end of the wagon and including a supporting frame, a transversely extending distributing member, upwardly and forwardly extending draft members on the frame, and a transverse member adapted to be loosely and detachably engaged by the 110 hooked members beneath the wagon.

115 In testimony whereof, I affix my signature in presence of two witnesses.
